UNITED STATES PATENT OFFICE

HERMAN PISTORIUS, OF SAGINAW, MICHIGAN.

INVALID-BED.

SPECIFICATION forming part of Letters Patent No. 321,754, dated July 7, 1883.

Application filed November 13, 1883. (No model.)

To all whom it may concern:

Be it known that I, HERMAN PISTORIUS, of Saginaw, in the county of Saginaw and State of Michigan, have invented certain new and useful Improvements in Invalid-Beds; and I do hereby declare the following to be a full, clear, and exact description of the invention, such as will enable others skilled in the art to which it pertains to make and use the same.

10 My invention relates to invalid-beds, the primary object being to provide a bed with devices whereby a patient may be raised without discomfort or liability to injury.

15 A further object of the invention is to provide means for lifting the head and upper portion of the patient's body at will.

20 A further object of the invention is to provide a bed with a sheet of peculiar construction, whereby the calls of nature may be conveniently attended to without the removal of the patient from the bed.

25 The invention consists of the improved devices, hereinafter fully described, and pointed out in the claims, for raising and lowering the patient upon the bed.

The invention further consists in the improved evacuation-sheet, which obviates the necessity of removing the patient from the bed.

30 The invention further consists in the means, hereinafter fully set forth, for raising and securing the head and upper portion of the body of the patient in a reclining position.

35 In the drawings, Figure 1 represents a perspective view of the bed provided with my improvements. Fig. 2 represents my improved grapple-frame. Fig. 3 represents the evacuation-sheet. Fig. 4 represents the devices for propping up the patient in a reclining position, and Fig. 5 is a modification.

40 A represents a bedstead, which may be of any preferred form. B represents a transverse bar supported above the bedstead by means of inclined braces C C, whose lower ends are formed with clamps e, for attachment to the side rails of the bed.

45 D represents a grapple device consisting of the longitudinal rod d, which is upwardly turned at one end. This upwardly-turned end of the rod d is secured to a yoke, E, whose ends are formed with hooks e, to engage one end of the sheet F, as clearly shown in Fig. 1.

G and H represent curved arms or yokes,

which are formed with a central sleeve, g, to receive the rod d, to which said arms or yokes are adjustably secured by means of thumb-screws h, passing through the sleeve g. The ends of the yokes G and H are formed with hooks o, to engage the edges of the sheet F, as shown in Fig. 1.

I represents a block-and-tackle device secured centrally upon the bar B at one end, and to an adjustable ring, J, secured upon the rod d, at the opposite end. The end of the rope j of the lifting device is secured upon a windlass mounted in a yoke-bearing, L, adjustably secured upon the rod d by means of the sleeve K and a thumb-screw, l.

From the construction thus far described it will be apparent that the entire sheet F, upon which the patient rests, may be readily raised from the bed, as shown in Fig. 1, to suspend the patient above the bed when desired.

As shown in Fig. 3, the sheet is formed with an evacuation-opening, M, and with a transverse flap, N, secured at one side of said opening and adapted to pass under said opening, to be buttoned to the under side of the sheet, as clearly shown in Fig. 3. The sheet F is also formed above the opening M of two thicknesses of material, the upper thickness, O, of which is adapted to be raised to prop up the patient, as shown in Figs. 1 and 4. The sheet F is also provided with any desired number of hooks, o, to facilitate the attachment of the sheet F to the grapping device D.

P represents a yoke-frame formed at its end with hooks p, to engage the corners of the upper layer, O, of the sheet, and connected by a block-and-tackle device, Q, with the transverse bar B. The lifting-rope R of the lifting device is used for propping up the patient in a reclining position, as shown in Fig. 4.

If preferred, the upper section, O, of the sheet F may be supported in its lifted position by braces S, secured to the side rails of the bedstead, as shown in Fig. 5; or other devices might be resorted to for supporting the patient in a reclining position.

The construction hereinbefore described affords a secure and convenient means for raising or moving the patient.

I do not limit myself to the precise construction shown and described, but reserve to myself the right to make all such changes in form

and construction as may properly fall within the scope of my invention.

Having fully described my invention, what I desire to claim and secure by Letters Patent is—

1. In an invalid-bed, the combination, with a bedstead, of a transverse bar and braces for supporting the latter, a frame suspended from said bar, and consisting of a longitudinal rod and yokes formed with hooks, and a sheet or hammock suspended from said frame, substantially as set forth.

2. In an invalid-bed, the combination, with a transverse bar and its supporting-braces, of a longitudinal rod suspended from said bar, a windlass located on said rod, pulleys secured, respectively, upon said bar and rod, an elevating-rope, a hammock, and adjustable yokes supporting the latter, substantially as set forth.

3. In an invalid-bed, the combination, with a transverse bar and its supporting-braces, of a longitudinal rod suspended from said bar, adjustable arms or yokes, adjustable rings or eyes, and elevating reels and cords, substantially as set forth. 25

4. In an invalid-bed, the combination, with a transverse bar and its supporting-braces, of a longitudinal rod suspended from said bar, arms or yokes supported upon said bar and formed with hooks, and a sheet or hammock formed with an opening, as described, and with flaps N and O, substantially as set forth. 30

In testimony whereof I have signed this specification in the presence of two subscribing witnesses. 35

HERMAN PISTORIUS.
